UNITED STATES PATENT OFFICE

2,648,106

SWINGING SASH WITH A WEATHER-
PROOFING LATCH

Edward P. Shater, Union City, N. J.

Application September 9, 1949, Serial No. 114,886

2 Claims. (Cl. 20—68)

1

This invention relates to new and useful improvements in window constructions and more particularly to revolving windows of the type used for ventilating homes, buildings, factories and the like where screens and storm sashes are not employed.

The primary object of the present invention is to provide a window structure including a swingable sash mounted in a casing and embodying novel and improved weather stripping means between the sash and the casing.

Another important object of the present invention is to provide a revolving sash of the aforementioned character in which the weather stripping means also functions as a means for preventing swinging movement of the sash relative to the casing when it is desired to retain the sash in its closed position.

A further object of the present invention is to provide a revolving window including a swingable sash, a casing for the sash, slideable weather strips carried by the casing for engaging the sash, and a manually operated means for retaining the strips out of engagement with the sash whereby the latter may swing, in an unrestricted arc, for opening thereof.

A still further aim of the present invention is to provide a revolving window that is simple and practical in construction, convenient to service and install, small and compact in structure, quickly and readily adjusted for opening and closing the sash forming part thereof, neat and pleasing in appearance, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a front elevational view of a window constructed in accordance with the present invention, and showing the upper and lower sash thereof in their closed position;

Figure 2 is an enlarged horizontal sectional view taken substantially on the plane of section line 2—2 of Figure 1;

Figure 3 is a view similar to Figure 2 but showing the lower sash partially open;

Figure 4 is a vertical sectional view taken substantially on the plane of section line 4—4 of Figure 2;

Figure 5 is an enlarged vertical sectional view taken substantially on the plane of section line 5—5 of Figure 1 and showing the weather strip

2

disposed out of the recess in the lower rail of the lower sash;

Figure 6 is a view similar to Figure 5 but showing the weather strip in the recess in the lower rail of the lower sash;

Figure 7 is an enlarged, fragmentary, front elevational view of the present window structure to illustrate the manner in which the weather strips are locked out of engagement with the sash;

Figure 8 is a horizontal sectional view taken substantially on the plane of section line 8—8 of Figure 7; and

Figure 9 is a vertical sectional view taken substantially on the plane of section line 9—9 of Figure 8.

Referring now to the drawings in detail, wherein, for the purpose of illustration, there is disclosed a preferred embodiment of the present invention, the numeral 10 represents the instant revolving window structure generally, including an upper sash 12, a lower sash 14, an upper casing 16 for the upper sash 12, and a lower casing 18 for the lower sash.

It is preferred that the casings 16, 18 and the sashes 12, 14 be constructed of suitable light weight, durable non-corrosive metal. However, any suitable material may be used depending upon the cost of installation for a particular job, the availability of material and the cost of manufacture, as well as the type of building structure associated therewith.

Since the casings 16, 18 are similar in construction and, further, since the sashes 12, 14 are also similar in construction, a description for one casing and one sash will suffice for both. Furthermore, it is understood that a single sash and casing, or any suitable number of sashes and casings may be employed, depending upon the size of window opening, light and ventilation required or desired.

The sashes 12 and 14 are substantially rectangular in configuration and each is composed of an upper rail 20, a lower rail 22, and side rails 24 and 26. The rails 20, 22, 24, and 26 are joined in any suitable manner, or form an integral structure, and support a panel 28 of translucent or transparent material, such as glass.

The casings 16 and 18 are also substantially rectangular in shape and each includes an upper portion 30, a lower portion 32 and side portions 34 and 36. The inner face of the side portion 36 is formed with a longitudinal groove 38 for receiving a tongue or extension 40 on the side rail 26 and the forward face of the side portion 34 is provided with a longitudinal groove 42 for

receiving a tongue or extension 44 on the side rail 24 in order to seal the side rails of the sashes to the side portions of the casings when the sashes are in their closed position.

Projecting laterally from the central portions of the upper and lower rails 12 and 14 are pivot pins or trunnions 46 that enter suitable recesses or depressions 48 provided in the inner and lower portions of the casings for individual horizontal swinging movement of the sashes relative to the casings. The pins 46 are secured to the sashes in any suitable manner so that they may be removed from the inside of the window structure 10 to facilitate a replacement or repair of parts.

The upper and lower portions 30 and 32 of the casings are formed with longitudinally extending grooves or channels 50 that slidably receive combined weather strips and retainer strips 52. The strips 52 are constructed of any suitable material and are provided with openings 54 adjacent their ends that receive bolts 56. The heads 58 of the bolts 56 are preferably square and are slidably received in intersecting vertical and horizontal grooves 60 and 62 formed in the walls defining the grooves 50, to hold the bolts against rotation relative to the strips 52.

The bolts 56 are also slidably received in intersecting vertical and horizontal grooves or slots 64 and 66 provided in the upper and lower portions of the casings. The threaded ends of the bolts 56 receive combined lock nuts and finger grips 68 and the inside surfaces of the portions 30, 32 are formed with recesses 70 in which the combined lock nuts and finger grips 68 are positioned to obviate any harmful projections or obstructions.

A pair of substantially U-shaped spring members 72 are secured in each of the grooves 50 and yieldingly urge the strips 52 into grooves 74 provided in the rails 20 and 22.

In practical use of the present invention, when the sashes are in their closed position, the strips 52 are received in the recesses or grooves 74, as shown in Figure 6, to hold the sashes against opening and to prevent the passage of water between the sashes and their casings.

To open the sashes, it is merely necessary to move the bolts 56 vertically in the slots 64 and horizontally across the slots 66, whereupon the strips 52 will be moved out of the recesses 74, as shown in Figure 5.

In view of the foregoing description taken in conjunction with the accompanying drawings, it is believed that a clear understanding of the device will be quite apparent to those skilled in this art. A more detailed description is accordingly deemed unnecessary.

It is to be understood, however, that even though there is herein shown and described a preferred embodiment of the invention, the same is susceptible to certain changes fully comprehended by the spirit of the invention as herein described and within the scope of the appended claims.

Having described the invention, what is claimed as new is:

1. In a window structure including a casing having a lower portion and a closure pivoted to

the casing for swinging movement and having a lower rail overlying the lower portion of the casing when the closure is in its closed position, said lower portion having an elongated horizontal groove therein, said lower portion also having a pair of vertical slots therein intersecting said groove adjacent the ends of the groove, a combined sealing and locking strip longitudinally and laterally slidable in said groove, said strip having a pair of apertures therein in registry with said slots, a pair of headed pins having shanks complementary to and extending through the apertures and slidably received in the slots, said pins each having a threaded end, said casing having recesses about said slots receiving the threaded ends of said pins and each of said recesses having a vertical wall parallel to said strip, nuts threaded on the threaded ends of said pins and engaging said wall of each recess to force the heads of the pins against the strip and thereby hold the pins against sliding movement in the slots and the strip against sliding movement in the groove, and springs in the groove slidably supporting the strip and yieldingly urging the strip from the groove for engaging the lower rail of said closure.

2. In a window structure including a casing having an edge portion and a closure pivoted to the casing for swinging movement and having a portion disposed adjacent and parallel to said edge portion when the closure is in its closed position, said edge portion having an elongated groove therein, said edge portion also having a pair of parallel slots therein intersecting said groove adjacent the ends of the groove and disposed parallel to the axis about which said closure is swingable, a combined sealing and locking strip longitudinally and laterally slidable in said groove, said strip having a pair of apertures therein in registry with said slots, a pair of headed pins having shanks complementary to and extending through the apertures and slidably received in the slots, said pins each having a threaded end, said casing having recesses about said slots receiving the threaded ends of said pins and each of said recesses having a wall parallel to the strip, nuts threaded on the threaded ends of said pins and engaging said wall of each recess to force the heads of the pins against the strip and thereby hold the pins against sliding movement in the slots and the strip against sliding movement in the groove, and springs in the groove slidably supporting the strip and yieldingly urging the strip from the groove for engaging the casing portion.

EDWARD P. SHATER.
